UNITED STATES PATENT OFFICE.

WILLIAM F. GRUPE, OF HUDSON HEIGHTS, NEW JERSEY, ASSIGNOR TO ENDLESS BELT CORPORATION, INC., A CORPORATION OF NEW YORK.

SELF-ADJUSTING TENSION MEANS.

1,391,185.

Specification of Letters Patent. Patented Sept. 20, 1921.

Application filed May 31, 1919. Serial No. 300,931.

To all whom it may concern:

Be it known that I, WILLIAM F. GRUPE, a citizen of the United States of America, residing at Hudson Heights, county of Bergen, State of New Jersey, have invented certain new and useful Improvements in Self-Adjusting Tension Means, of which the following is a specification.

This invention relates to self-adjusting tension means.

In the use of certain types of belts, particularly belts subjected to curved or angular deformation, such as belts for cigarette making machines, it is desirable to attain a predetermined tension in the belt and attempts have been heretofore made for attaining such result, but such heretofore proposed arrangements have been ineffectual. Such heretofore proposed arrangements are also defective by reason of the absence of the capability of adjusting the tension from time to time in accordance with the desired requirements in the operation of the belt.

In the use of feeding belts for cigarette making machines, the belt is of woven fabric and serves to feed the cigarette making materials through a so-called forming shoe whereby the inclosing paper and the inclosed cigarette tobacco are forced by the shoe to be curved into cylindrical shape, causing the edges of the paper to overlap, at which state adhesive is applied and the overlapping edges secured to one another to form a resultant cigarette of indefinite length, which at a subsequent stage is cut into desired lengths, the ordinary individual cigarettes. During the stage of curved formation of the cigarette materials, the belt is deformed as stated above, and at a later stage assumes its normal uniplanar position.

I have discovered, that, in order to effect proper feeding of the paper strip and the cigarette tobacco conveyed on the paper strip, it is desirable to maintain a certain tension in the belt, effective particularly for the portion of travel of the belt between the points of initial and final engagement of the belt with the paper strip.

In carrying out my invention, I provide an idler carried by a suitable movable support and means controlled by a regulatable weight for controlling the position of such idler whereby to regulate the tension of the belt, the feeding of the paper strip and

cigarette tobacco and the formation of the resultant cigarettes. Such provision of means operate to automatically maintain such predetermined pressure notwithstanding elongation or other variation of the belt incident to use. The tension is adjustable simply by adjusting or by replacing a corresponding weight to provide a universal self-adjusting tension means for varying types of fabric belts and varying types of shoes or formers.

Further features and objects of the invention will be more fully understood by the following description and accompanying drawings, in which—

Fig. 1 is a perspective view of one embodiment of my tension means in combination with a cigarette making machine, the parts of such cigarette making machine being indicated diagrammatically;

Fig. 2 is a detail end elevation as viewed from line 2—2 of Fig. 1, in the direction of the indicated arrow; and

Fig. 3 is a side elevation of the tension means.

Referring to Figs. 1, 2 and 3, the cigarette feeding belt is indicated at 1 and, as shown, the path of travel of the belt 1 is about the driving wheel 2, thence over the fixed idler 3, thence through my tension adjusting means, indicated generally at 4, thence over the guiding means 5, at which location 6 the belt 1 makes initial contact with the paper strip 7, onto which is fed by suitable feeding means the cigarette tobacco indicated at 8. The forming shoe is indicated at 9, through which the belt 1 travels and is forced by the curved sides of the shoe to be curved, to thereby cause the paper strip 7 and the cigarette tobacco 8 therein to be "rolled" and upon application of suitable adhesive the resultant cigarette of indefinite length 10 is formed. The guide means 5 is preferably an anti-friction roller.

The course of travel of the belt through the aforesaid regions of travel is indicated by the arrows 11.

Such tension means comprises the relatively fixed idler 12 rotatably mounted on the stud 13 carried by the side of the cigarette making machine 14. The tension adjusting idler 15, is preferably disposed between the idler 3 and the idler 12. Such idler 15 is mounted on the stud 16, tapped, into the plate 17. The plate 17 is a segment

hung on the stud 13. Behind the plate 17 is provided the plate 18, which may also be hung on the stud 13, and positioned by means of the stud 19. The stud 19 is provided with the exterior head 20 and with the guiding collar 21.

The segment 17 is provided with the arcuate slot 22 through which projects the stud 19. The collar 21 serves as a guide for the edges of the arcuate slot 22. The sector 17 is provided with the teeth 23 at its arcuate edge, meshing with the pinion 24. Fixed to the pinion 24 is the sheave 25, and the pinion 24 and sheave 25 are loosely mounted 15 on the stud 26, having the external head 27 and retaining collar 28. The stud 26 is tapped in the plate 18 or in the side of the body of the cigarette machine 14, or other suitable support.

20 To the sheave 25 is suitably fixed the attached end 29 of the cord or wire 30, on which freely hangs a replaceable weight 31, or equivalent.

The center of the sector 17 is coincident 25 with the axis of the stud 13 on which the section is hung; the radial arms of the leverages involved may be in the ratio of two to one as in the usual form of the invention, whereby the weight 31 is one-half of the 30 force, *i. e.*, tension exerted by the idler 15 on the belt 1.

The operation of the device will be largely apparent from the above description and it will be noted that the weight 31 exerts an 35 effective leverage on the idler 15 by the relative movement between the pinion 24 and the sector 17, on which latter the idler 15 is carried. The effective leverage is a definite multiple of the replaceable weight, or equivalent, for all positions of the idler 15 relative to the path of travel of the belt.

Upon variation in the length of the belt the degree of friction between the belts and sides of the forming shoe, the belt is notwithstanding maintained at the desired tension, the idler 15 oscillating about the center of oscillation of the segment 17, such oscillation of the segment 17 oscillating the pinion 24 and sheave 25, with resultant rise 45 or fall of the weight 31, or equivalent means.

It will be noted that such arrangement in-

sures uniform tension in the belt and is effective at all times, whereas heretofore proposed arrangements required manual adjustment upon varied conditions of operation of the belt and associated parts. This advantage is a distinct advance, when the high rate of travel of the feeding belt and the high output in a number of cigarettes formed by each cigarette forming machine is borne in mind.

Whereas I have described my invention by reference to specific forms thereof, it will be understood that many changes and modifications may be made without departing 65 from the spirit of the invention as defined by the appended claims.

I claim.

1. The combination of a belt, of means for exerting a predetermined pressure on said belt, comprising an idler, a segment, means for mounting said idler on said segment and means for exerting a constant pressure on said segment. 70

2. The combination with a belt, of means for maintaining a determined pressure on said belt, comprising an idler, a segment, means mounting said idler in fixed relation to said segment, a pinion, means for mounting said pinion on a fixed support, a sheave, 80 means for connecting said sheave in fixed relation with said pinion, and means for exerting a predetermined constant force on said sheave. 75

3. The combination with a belt, of an idler 85 adapted to engage said belt, a segment, means for mounting said idler on said segment, a pinion, a fixed stud movably supporting said pinion, a sheave in fixed relation with said pinion, a yieldable element 90 passing about said sheave and a replaceable weight connected to said yieldable element. 90

4. The combination with a belt, of an idler, a segment mounted concentrically with said idler, a second idler, means for mounting said second idler in fixed relation with said segment, a pinion and means for exerting a constant pressure on said pinion. 95

In testimony whereof I have signed this specification this 26th day of May 1919.

WILLIAM F. GRUPE.
